(57) **CLAIM**

The ornamental design for a frame charging case as shown and described.

DESCRIPTION

FIG. 1 is a front perspective view of a frame charging case in a closed configuration.

FIG. 2 is a rear perspective view thereof.

FIG. 3 is a top plan view thereof.

FIG. 4 is a bottom plan view thereof.

FIG. 5 is a front elevation view thereof.

FIG. 6 is a rear elevation view thereof.

FIG. 7 is a side elevation view thereof.

FIG. 8 is a front perspective view of the frame charging case in an open configuration with its lid removed and placed beneath the case.

FIG. 9 is a rear perspective view thereof.

FIG. 10 is a top plan view thereof.

FIG. 11 is a bottom plan view thereof.

FIG. 12 is a front elevation view thereof.

FIG. 13 is a rear elevation view thereof; and,

FIG. 14 is a side elevation view thereof.

The shade lines in the Figures show contour and not surface ornamentation. The broken lines in the Figures show portions of the frame charging case and its surrounding environment that form no part of the claimed design.

1 Claim, 6 Drawing Sheets
